(57) **CLAIM**

The ornamental design for an HVAC airflow hood, as shown and described.

DESCRIPTION

FIG. 1 is a top perspective view of an HVAC airflow hood illustrating our new design, according to a first embodiment.

FIG. 2 is a bottom perspective view of an HVAC airflow hood illustrating our new design, according to a first embodiment.

FIG. 3 illustrates a front view of an HVAC airflow hood illustrating our new design, according to a first embodiment.

FIG. 4 illustrates a rear view of an HVAC airflow hood illustrating our new design, according to a first embodiment.

FIG. 5 illustrates a left side view of an HVAC airflow hood illustrating our new design, according to a first embodiment.

FIG. 6 illustrates a right side view of an HVAC airflow hood illustrating our new design, according to a first embodiment.

FIG. 7 is a top view of an HVAC airflow hood illustrating our new design, according to a first embodiment.

FIG. 8 is a bottom view of an HVAC airflow hood illustrating our new design, according to a first embodiment.

FIG. 9 is a top perspective view of an HVAC airflow hood illustrating our new design, according to a second embodiment.

FIG. 10 is a bottom perspective view of an HVAC airflow hood illustrating our new design, according to a second embodiment.

FIG. 11 is a front view of an HVAC airflow hood illustrating our new design, according to a second embodiment.

FIG. 12 is a rear view of an HVAC airflow hood illustrating our new design, according to a second embodiment.

FIG. 13 is a left side view of an HVAC airflow hood illustrating our new design, according to a second embodiment.

FIG. 14 is a right side view of an HVAC airflow hood illustrating our new design, according to a second embodiment.

FIG. 15 is a top view of an HVAC airflow hood illustrating our new design, according to a second embodiment; and,

FIG. 16 is a bottom view of an HVAC airflow hood illustrating our new design, according to a second embodiment.

Portions illustrated in broken lines in all views are shown for illustrative purposes only and form no part of the claimed design.

1 Claim, 16 Drawing Sheets
